partnership

Application December 16, 1938, Serial No. 81,811

Term of patent 7 years

To all whom it may concern:

Be it known that I, Louis Cruveilher, a citizen of the United States, residing at New York, in the county of New York and State of New York, have invented a new, original, and ornamental Design for a Plate or the like, of which the following is a specification, reference being had to the accompanying drawing, forming part thereof.

In the drawing:

Fig. 1 is a top plan view of a plate, or the like showing my new design;

Fig. 2 is a sectional view on line 2—2 of Fig. 1;

Fig. 3 is a detail sectional view on line 3—3 of Fig. 1;

Fig. 4 is an enlarged detail sectional view on line 4—4 of Fig. 1.

The characteristic feature of my design resides in the combination of the narrow and embossed scalloped border in association with an undulating surface on the rim of said plate, the various undulations having their crests midway between the points of the scallop.

I claim:

The ornamental design for a plate or the like, as shown and described.

LOUIS CRUVEILHER.
